UNITED STATES PATENT OFFICE.

ALVIN R. NEALE, OF ADEL, IOWA.

MECHANISM FOR OPERATING DOORS.

1,426,591.

Specification of Letters Patent. Patented Aug. 22, 1922.

Application filed November 28, 1919. Serial No. 341,233.

To all whom it may concern:

Be it known that I, ALVIN R. NEALE, a citizen of the United States, residing at Adel, in the county of Dallas, State of Iowa, have invented a new and useful Mechanism for Operating Doors, of which the following is the specification.

This invention relates to door operating mechanism, and especially that designed to operate double doors, as used in garages, livery barns, etc. In garage doors it is desirable to have means whereby the outside doors may be opened and closed without the operator leaving the office.

It is therefore the object of my invention to provide a door of simple, durable and inexpensive construction so arranged that a pair of doors may be simultaneously operated in a doorway by a single lever spaced 20 at any convenient distance from said doors.

It is more particularly the object of my invention to provide an improved means for mounting and operating double doors, such as are used in garages.

These and other objects will be apparent to those skilled in art and need not be mentioned in detail.

I attain these objects by the mechanism illustrated in the accompanying drawings, 30 in which:

Fig. 1 is a side elevation of my door operating mechanism showing a portion of the room in which the doors are mounted in section.

Fig. 2 is a diagrammatic view showing the manner in which the operating cables are mounted on the sheaves.

Fig. 3 is a detail sectional view taken on the line 3—3 of Fig. 1.

Fig. 4 is a detail view showing the lower portion of one of the operating shafts in section and the manner of pivotally mounting the same.

Fig. 5 is a detail side elevation of one of the operating sheaves and showing the manner in which it is mounted.

Fig. 6 is a detail view showing one of the adjusting devices.

Fig. 7 is a sectional view taken on the line 50 7—7 of Fig. 5.

I have used the reference numeral 10 to indicate the door frame which is of the ordi-

nary construction and the numeral 11 to indicate a support which is placed across the joists of the ceiling and is designed to 55 carry thrust bearing members 12. Each of these bearing members 12 is designed to receive a vertical shaft 15 so mounted as to lie adjacent to the sides of the door opening in the frame 10. The lower end of each 60 of the shafts 13 is provided with a pin 14 secured to the floor by means of a bracket 15. The pin extends up into the shaft 13 which may be formed hollow at the lower 65 end or preferably, a hollow pipe. The upper end of each of the shafts 13 is provided with a sheave 16, each of which is provided with grooves 17 and 18. A notch 19 is provided in the rib between said grooves as illustrated in Fig. 7. This notch 19 is for 70 the purpose of providing means for preventing the cables 20 from slipping in the grooves, and is accomplished by passing the cable in the groove 17 then through the notch 19 into the groove 18, thereby forming a kink 75 in the cable at the portion that lies in the notch 19. By this arrangement it will be seen that when the cable is passed once around the sheave, the cable will not slip when a greater pull is applied to one cable 80 than the other. The operation of these sheaves will be more fully set forth.

A door 21 is secured to each of the shafts 13, by means of strap irons 22. These straps are passed around the shafts 13 as illustrated in Fig. 3 and secured to the doors by means of rivets 23. A rivet 24 is passed through each of the strap irons 22 and through the shafts 13 for the purpose of preventing the straps from slipping on said 85 shafts and at the same time carry the weight 90 of the doors. When the doors are in a closed position they are in line with each other, as clearly shown in Fig. 1.

By this construction it will be seen that 95 the weight of the doors will be carried by the sheaves engaging the bearing members 12, the pins 14 being merely for the purpose of forming pivots for the lower ends of the shafts.

For operating the doors 21, I have provided a third vertical shaft 25 mounted similar to those already described but in a position adjacent to an inner wall of an ad-

joining room or any other convenient place. The said shaft 25 is provided with a handle 26 which may be extended through a slot 27 in the wall so that the said handle may be 5 operated from inside of an adjoining room to the one in which the doors are located. The upper end of the shaft 25 is provided with a sheave 30 similar to those already described. For operating the doors, a cable 20 10 is secured to the sheave 28 by passing it once around said sheave then once around the sheave 29 in the opposite direction to that of 28, thence once around the sheave 30 and back to the sheave 28, the cables in each case 15 passing through the notches 19, as above described. In the cable extending between the sheaves 30 and 28, and 28 and 29, I have provided turn-buckles 31 and 32 which are for the purpose of taking up slack in the 20 cables and also for the purpose of aligning the doors 21 relative to each other.

It will be seen that if the turn-buckle 32 is loosened and the turn-buckle 31 tightened, the left hand door will be rotated in an anti-clockwise direction, or if it is desired to move the said door in the opposite direction it may be accomplished by merely reversing the direction of the rotation of the turn-buckles. By rotating both of the turn-buckles in the same direction, the cable may be tightened.

Thus it will be seen I have provided a simple but effective method of aligning the doors and at the same time taking up the slack in the cable. To operate the doors, the operator grasps the handle 26 and moves it to a position shown in dotted line in Fig. 2 which will cause the cable to move in the direction of the arrows, and the doors swing 40 to the position shown in dotted lines. This may be accomplished without the operator leaving his position in the office.

Thus it will be seen I have provided doors which will hang rigidly without sagging, 45 due to the fact that they are secured to the shaft 13 by means of the straps 22, and the fact that the shafts are of a considerable length, the operating mechanism may be easily and readily adjusted and at the same

time the doors may be properly brought in 50 alignment with each other when in a closed position, by means of the turn-buckles.

I claim:

1. A door opening device comprising door operating shafts and a manually operated 55 shaft, means for operatively mounting said shafts, a double grooved sheave having a communicating groove on corresponding ends of each of said shafts, a cable for operatively connecting all of said shafts by passing part way around in one of the grooves of 60 each sheave, thence through the communicating groove to the opposite groove, substantially as described and for the purpose stated. 65

2. The combination of a frame having a door opening, a vertical shaft mounted adjacent to each side of said door opening, means for rigidly clamping the edge of a door adjacent to each of said shafts, a 70 thrust bearing above said door opening for rotatively mounting each of said shafts and carrying the weight of said doors, an operating shaft parallel to said vertical shaft, a handle on said operating shaft, a double 75 grooved sheave having a communicating groove, on the upper end of each of said shafts and an operating cable designed to pass part way around in one of said grooves, thence through the communicating groove 80 to the opposite groove, substantially as described and for the purpose stated.

3. A door opening device comprising door operating shafts and a manually operated shaft, means for operatively mounting said 85 shafts, a double grooved sheave having a communicating groove on corresponding ends of each of said shafts, a cable for operatively connecting all of said shafts by passing part way around in one of the 90 grooves of each sheave, thence through the communicating groove to the opposite groove, the said cable being provided with an adjusting means between two sets of said 95 sheaves, substantially as described and for the purpose stated.

ALVIN R. NEALE.
